UNITED STATES PATENT OFFICE.

SANFORD GASSER, OF SHERMAN, MICHIGAN.

RAIL-HOLDER.

1,092,525.

Specification of Letters Patent.

Patented Apr. 7, 1914.

Application filed September 2, 1913. Serial No. 787,766.

To all whom it may concern:

Be it known that I, SANFORD GASSER, a citizen of the United States, residing at Sherman, in the county of Wexford and State of Michigan, have invented certain new and useful Improvements in Rail-Holders; and I do hereby declare the following to be a full, clear, and exact description of the invention, such as will enable others skilled in the art to which it appertains to make and use the same.

My invention relates to new and useful improvements in rail holders, and has for its object the provision of such a device to prevent creeping or spreading of the rails.

An important object of my invention resides in the provision of a device above described which consists of a pair of rail clamps that are carried terminally upon a bar which is laid transversely of the rails, and means for adjustably securing the clamps.

A further object of my invention resides in the provision of a device above described which is constructed of few parts, reliable in its operation and cheap to manufacture.

With these and other objects in view as will become more apparent as the description proceeds, the invention consists in certain novel features of construction, combination and arrangement of parts as will be hereinafter fully described and claimed.

For a complete understanding of my invention, reference is to be had to the following description and accompanying drawings, in which—

Figure 1 is a top plan view illustrating my device in operative clamping engagement with the rails, Fig. 2 is a transverse sectional view taken on the line 2—2 of Fig. 1, Fig. 3 is a side elevation, Fig. 4 is a sectional view taken on the line of 4—4 of Fig. 3, illustrating the clamps in operative engagement with the rails and the bolt for securing the same, Fig. 5 is a detail sectional view of the bar for connecting the rail clamps, illustrating the upstanding lugs formed on the terminals of the bar, and Fig. 6 is a detail perspective view of one of the clamping members.

Referring to the drawings, the numeral 1 designates a metallic bar forming the connecting medium for the rail clamps to be hereinafter described. The bar 1 is to be laid transversely of the rails designated A as an entirety, at a point suitably spaced

from the ties and beneath the rails. A pair of upstanding apertured lugs 2 are formed integrally with the terminals of the bar 1, and are adapted to have secured thereto the rail clamps.

The rail clamps, forming a part of my invention are designated as an entirety by the numerals 3 and 4, and as they are identical in construction, it is thought necessary to describe only one of them. The clamp 3 consists of a pair of coacting angular clamping members 5 and 6 that are adapted for engagement with the rail base 7 upon opposite sides thereof, and are each provided with a pair of downwardly extending lugs 8 and 9. The lugs 8 and 9 are apertured as at 10, and when the clamping members 5 and 6 have been fitted in engagement with the rail base 7, the lugs 8 and 9 are moved so that the apertures therein align with the aperture in the lug 2. A bolt 11 is inserted through the lugs 8 and 9 and one of the lugs 2, and is held against removal therefrom by means of a nut 12 threaded upon the screw threaded terminal 13 of the bolt 11. It is therefore apparent that when the clamping members 5 and 6 have been fitted in clamping engagement with the rail base 7 after the manner described, that an effectual clamping of the rails is provided so that all tendency of the rails to creep or spread is eliminated.

By means of the bolt 11 and the nut 12 the clamping members may be adjusted as desired.

It is apparent with reference to the foregoing description that the clamps 3 and 4 being connected by the bar 1 and secured thereto after the manner described, serve to hold the rails against any creeping or spreading tendency.

When the device is in clamping engagement with the rails the upstanding apertured lugs upon the terminals of the bar 1 are disposed beneath the rail bases 7 approximately centrally of the side edges thereof and by this arrangement the device may be utilized to a certain extent as a track gage.

By disposing the ends of the bar 1 as above described the possibility of accidental derangement of the clamp is eliminated. As the construction of the device is comparatively light and where the ends of the bars are disposed beyond the rails, heavy objects falling from trains and engaging the ex-

tended ends of the bar would cause the derangement of the clamping members or breakage thereof.

While I have shown and described the preferred embodiment of my invention, it will be understood that minor changes in construction, combination and arrangement of parts may be made without departing from the scope and spirit of the invention as claimed.

Having thus described my invention, I claim:

In a device of the character described the combination with the rails of a track of a rail holder adapted to be laid transversely of the rails, said rail holder comprising an elongated metallic bar having up-

standing integral apertured lugs on its terminals, a pair of angular clamping plates adapted for engagement with the rail bases 20 adjustably secured to the upstanding lugs on said bar, a bolt inserted through the clamping plates and lugs, said lugs being disposed approximately centrally of the side edges of the rail bases of said rails when the clamping plates are in clamping engagement with the rail bases of the rail and a nut threaded 25 upon said bolt.

In testimony whereof I affix my signature in presence of two witnesses.

SANFORD GASSER.
